UNITED STATES PATENT OFFICE

2,681,690

SUPPLEMENT SEAT FOR DENTAL CHAIRS

Carroll W. Johnson, Chicago, and John T. Clark,
Cicero, Ill.; said Clark assignor to said Johnson

Application February 6, 1952, Serial No. 270,184

4 Claims. (Cl. 155—81)

1

This invention relates to an improvement in operator supports for use with chairs in which a person is seated. More specifically, this invention relates to a support embodying a supplemental seat for use with a dental chair, barber chair or the like.

As is well known, a dentist or barber or other person performing work on a subject seated in a chair should be provided with a support so that such person may perform his work without requiring him to spend long hours in a standing position. In providing a support on which such a person may be seated while performing his work, it is desirable that the support be given a widely varying range of movement with respect to the chair. It is, therefore, a primary object of this invention to provide a supplemental seat which has a plurality of ranges of movement.

It is a further object of this invention to provide a supplemental seat for a chair which may be readily moved by the person occupying the supplemental seat with a minimum of effort.

Another object is to provide an improved means for adjusting a supplemental seat toward and away from the dental or other chair with which the supplemental seat is employed.

A further object of this invention is to provide a supplemental seat which may be adjusted radially with respect to the supporting connection between the dental or other chairs and the supplemental seat.

Other purposes will appear from time to time in the course of the specification and claims.

The invention is illustrated more or less diagrammatically in the accompanying drawings, wherein:

Figure 1 is a plan view of the supplemental seat and its supporting structure with relation to the primary seat or chair with which it is used;

Figure 2 is an elevational view of the supplemental seat shown in Figure 1, taken on line 2—2 of Figure 1;

Figure 3 is a sectional view of the supplemental seat shown in Figure 2, taken along line 3—3 of Figure 2;

Figure 4 shows an element of the seat support shown in Figures 1 through 3 with one end cut away;

Figure 5 shows a plan view of another element of the seat support;

Figure 6 shows an elevational view of one of the supplemental seat support members;

Figure 7 shows a sectional view of an adjustable feature of the supplemental seat support, taken along lines 7—7 of Figure 2.

Like parts are indicated by like symbols throughout the specification and drawings.

Referring now in detail to the drawings, 2 indicates an annular supporting base for a dental

2

chair or the like. It will be understood by those skilled in the art that the base 2 is a conventional support for chairs in which a subject or patient is seated.

5 A supporting base plate 4 for the supplemental seat is adapted to be inserted between the chair base 2 and the floor F of a room in which the chair is mounted. The base plate 4 is preferably formed with an arcuate end portion 6 which extends outwardly from the base 2 of the chair. Base plate 4 may be inserted at any convenient position around the periphery of the chair base 2.

A supplemental seat supporting member, indicated generally at 8, is pivotally mounted on the base plate 6. This pivotal mount may take the form of an upstanding pintle 10 received within a hub 12 of the supplemental seat support. It will be seen that the support 8 includes an elongated portion 14 forming an arch, with one end terminating in the hub 12 and the other end terminating in an outer supporting portion 16.

10 The supplemental seat support, including the elongated portion 14, provides, in effect, a radius arm structure for movement about the pivot 10. The supplemental seat supporting member 8 is provided with suitable antifriction means for supporting the outer end 16 of the support. The antifriction means may take the form of rollers 18 suitably journaled for rotating movement in a cut-away portion 20 of the seat support.

15 A control box 22 is mounted on the supplemental seat supporting structure as by means of a pivot member 24 and may be swung back and forth under the portion 14. As shown, the pivotal connection between the control box and the supplemental seat support takes the form of a bolt having a portion 26 in threaded engagement with the seat support. A spring 28 is disposed between the control box and the head of the bolt 30 to maintain the control box in a desired vertical position. The control box 22 includes members 34 and 36 which are adapted to control various mechanisms that the person using the supplemental seat may desire to employ, such as dental tools. A roller 32 is adapted to support the outer end of the control box on floor F.

20 A seat 38 is mounted upon the seat support 8 in a manner to be described. The seat 38, as shown, is circular in shape and is provided with customary upholstery padding 40.

25 A connection, indicated generally at 42, providing for pivotal movement and sliding movement of the seat 38 with respect to the support 8, is employed between the seat 38 and the support 8. In the preferred form of the invention, this connection includes a carriage 44 mounted for sliding movement upon an upstanding rod 46 on the support 8. As will be seen in Figure 2,

the carriage or housing 44 has a length generally equal to the diameter of the seat 38.

The seat 38 is pivotally mounted upon a member 48 rising from the carriage. The pivotal connection between the upstanding member 48 and the seat 38 includes an annular collar 50 abutting against a shoulder 52 on the upstanding member for rotation with respect thereto. Suitable means, such as rivets or screws 54, are employed to fix the seat with respect to the annular collar. A bolt 56 may be threadably received within the member 48 and have its head portion 58 adapted to overlie the annular collar and, thus, hold the seat 38 against removal from the upstanding member 48.

The carriage 44 preferably is in the form of a channel member having bottom portions 60 turned in from the side portions 62. Fixed at the top of the upstanding support rod 46 is a roller supporting member 64. The roller supporting member 64 may be fixed to the upstanding rod 46 by any suitable means, such as a depending sleeve 66 and a pin 68. Longitudinally spaced pairs of rollers 70 are journaled at opposite ends of the member 64 and are adapted for rolling contact with either the top of the carriage 72 or the inturned ends 60. It will be understood that the carriage 44 is provided with closed ends 74 which confine the movement of the carriage with respect to the rollers to the length of the carriage. It will be understood here that the rolling contact of the rollers with the carriage provides a convenient adjustment toward and away from a person seated in the dental or barber chair. A person employing the supplemental seat 38 may adjust his position with respect to a patient or person seated in the chair by merely thrusting his feet against the floor F.

An adjustable connection is provided between an upstanding portion 76 of the support 8 and the upstanding rod 46. This adjustable connection, as shown, employs a spring-biased pin 78 adapted for engagement with a plurality of apertures 80 aligned longitudinally of the support rod 46. The spring-biased pin 78 is provided with a handle 82 and is mounted in a housing 84 on the upstanding portion 76. An operator of the supplemental seat 38 may thus adjust the seat 38 to any desired height by inserting pin 78 in any aperture 80.

It will be realized that, whereas a practical and operative device is herein described and illustrated, nevertheless many changes in size, shape, number and disposition of parts may be made without departing from the spirit and intent of the invention. It is, therefore, wished that the description and showing herein be taken as in a broad sense, illustrative or diagrammatic, rather than as a limitation to the precise showing herein.

The use and operation of the invention are as follows:

The base plate 4 of the supplemental seat support may be placed at any convenient position around the periphery of the chair base 2. The operator employing the supplemental seat 38 has the advantage of a plurality of ranges of movement with respect to the chair. The entire support shown has one range of movement about the periphery of the chair base 2. The supplemental seat supporting structure 8, which constitutes, in effect, a radius arm structure for swinging movement about pivot 10, provides one of these ranges. While seated on the seat 38, a person may swing about the pivot 10 to any position on

the arc of movement defined by the distance between the pivot 10 and the seat 38. At any position along this arc of movement, the operator can increase or diminish the radial distance between the pivot 10 and the seat 38 by merely thrusting his feet against the floor and sliding carriage 44 back and forth along the rollers 70, thereby providing a range of movement with respect to pivot 10 and support 8. At any of these radial positions with respect to pivot 10, the operator can swing himself on the seat pivot 48 and thus face in any desired position with respect to the person seated in the chair, providing a circular range of movement with respect to carriage 44.

We claim:

1. In a supplemental seat and support for a dental chair, a base insertable beneath the base of said dental chair, a radius arm structure mounted for rotation on said base about a predetermined axis, an upstanding support member formed at one end of said arm structure and spaced away from said axis, antifriction means carried by said radius arm structure and spaced from said axis, a plurality of roller elements mounted at the upper end of said support member, a generally elongated housing receiving said roller members and slidably on said roller members, the upper portion of said housing having a pivot member formed thereon and an operator-supporting seat mounted on said pivot member to thereby allow movement of said seat and said housing in a linear direction while allowing rotation of said seat with relation to said housing.
2. In a supplemental seat and support for a dental chair, a base insertable beneath the base of said dental chair, a radius arm structure mounted for rotation on said base about a predetermined axis, an upstanding support member formed at one end of said arm structure and spaced away from said axis, antifriction means carried by said radius arm structure and spaced from said axis, a plurality of roller elements mounted at the upper end of said support member, a generally elongated housing receiving said roller members and slidably on said roller members, the upper portion of said housing having a pivot member formed thereon, and an operator-supporting seat mounted on said pivot member, the diameter of said operator-supporting seat being on the order of the length of said housing, said seat and pivot being positioned generally centrally of said housing to thereby overlie said housing at each extended position of said housing with respect to said roller elements.
3. In a supplemental seat and support as recited in claim 2 wherein said housing includes side walls and inwardly extending bottom portions from each said side wall to thereby provide a track for said roller elements, said inwardly extending portions being spaced sufficiently to define a longitudinally extending open passage for the movement of said upstanding support member therethrough.
4. The structure set forth in claim 2 characterized by and including a control box mounted on said radius arm structure, said housing extending in a direction toward said control box.
